STRUCTURE STRAIGHTENER

Harry J. Freeman, Columbus, Ohio, assignor to
The Pennsylvania Railroad Company, Philadelphia, Pa., a corporation of Pennsylvania

Application March 18, 1942, Serial No. 435,147

8 Claims. (Cl. 153—48)

This invention has general reference to means designed for restoring distorted structural areas to normal planar condition; while it relates, more particularly, to apparatus or devices adapted for the straightening of deformed railroad car bodies. Means of the last mentioned species, heretofore devised, have either necessitated the removal of the distorted part or parts of the car or truck, with an expenditure of much unnecessary time and labor; or such means has been of a stationary and non-portable character with resultant loss in service time for the damaged car or truck.

The primary object of this invention is to overcome the above noted disadvantages by provision of a straightener-device which can be easily moved to the location of a distorted structure or the like, readily attached thereto, and the mis-shapen part or area promptly restored to desirable normality with a minimum expenditure of time and labor.

Another object of this invention is to provide a portable straightener-device preferably, although not essentially, designed for promptly restoring the distorted end or ends of railroad cars, and the like, to proper position irrespective of whether the car be loaded or empty.

A further object is to provide a railroad car or truck end straightening-device, of the species indicated in the preceding paragraph, which includes provisions whereby it is automatically connectable to the standard A. A. R. coupler customarily located at both ends of freight cars, as well as adjustable support for power actuated means adapted to effect pressure abutment against the mis-shapen part or parts to effect the straightening-out thereof.

A still further object is the provision of a power-actuable railroad car end straightening-device which is positive in action and easily adjustable to effect the restoration of loaded or empty box or gondola car distorted ends to proper shape, whether they be made of flat or corrugated material.

Additional objects of this invention involve certain improved features of construction, in a device of the species above defined, as well as the novel combinations and arrangements of the various parts hereinafter disclosed.

While the foregoing definitions are indicative, in a general way of the objects of this invention, others with ancillary advantages will be evident to those skilled in the art upon a full understanding of the construction, arrangement and operation of the device hereafter fully described; but it will be further appreciated that the invention

is susceptible of other embodiment or structurally modified forms, than the one chosen for illustrative purposes in the accompanying drawings, and coming equally well within the terms of the concluding claims.

In the drawings:

Fig. 1 is a side elevation of a preferred form of car or truck end straightening-device, in accordance with this invention, coupled to a gondola car and in position for re-shaping the adjoining bulged-out end thereof, and with parts in section for the better clarification of structural details.

Fig. 2 is a front end elevation of the straightening-device.

Fig. 3 is a corresponding view at the rear end thereof.

Fig. 4 is a horizontal section, taken approximately as indicated by the angle-arrows IV—IV in Fig. 1.

Fig. 5 is a similar section, on the plane V—V of Fig. 1.

Figs. 6 and 7 are detail sections taken, respectively, on the arrowed planes VI—VI and VII—VII in Fig. 5, and drawn to larger scale for purposes of clarity.

In describing the form of this invention, exemplified in the above captioned drawings herewith, specific terms will be employed for the sake of clarity, but it is to be understood the scope of said invention is not thereby limited; each such term being intended to embrace all equivalents which perform the same function for an analogous purpose.

Referring more in detail to the drawings which conveniently illustrate a form of this invention well adapted for straightening the distorted ends of railroad gondola, or box, cars either loaded or empty, the reference character 1 indicates spaced fragmentary lengths of rail forming a trackway; while 2 generally designates a broken portion of a standard type "gondola" car, having the sheet metal end 3 outwardly bellied or distorted; and 4 comprehensively denotes the straightening-device of this invention.

This straightening-device 4 comprises a structure conveniently composed of opposed channels, preferably having the flanges 5, 5' inwards, said channels defining vertical columns or posts 6 for support of a coupler 7 and the "jack" 8, which will be later on again referred to. Rigidly secured, as by a weld 9, to the lower outer web portion of each post 6, is a rearwardly-extending inverted T-section or base member 10, and in planar alignment therewith is a forwardly-directed angle-section 11, having the vertical flange united

to the leg of said T-section by a weld 12, and its horizontal flange 13 inward and correspondingly secured to the abutting front flange 5 of the post 6. Thus it will be readily seen that the flange 14 of the T-section bar 10 with the flange 13 of the angle-section bar 11 provide a comparatively extensive base support for maintenance of the straightening-device 4 upright; while it is to be noted the T-sections 10 are substantially longer than the angle-sections 11, for a reason hereafter explained, and to better restrain the device 4 against deflection from the vertical, when seated on the head or ball of track rails 1. To secure the posts 6 in rigid spacial relation, use is conveniently made of a T-section upper brace 15 having its ends suitably united, as by end welds 16, to the adjoining inner face of the web portions of said posts; while the top surface of the flange 17 of said brace 15 is preferably located coplanar with the upper edges of the posts 6. Angle-section struts 18 are conveniently welded at 19, 20, respectively to the upper outer or rear flanges 5' of the posts 6, and to the inner faces of the leg portions of the T-section base members 10; and, with intervening diagonal braces 21, preferably of angle-section, united thereto by welds 22 and to one another by similar means 23, jointly serve to rigidify the device 4, as a fabricated frame-like structure.

The supporting means for the coupler 7 preferably comprises a transverse channel-section carrier or beam 24, conveniently secured by welds 25, 26 across the forward flanges 5 of the posts 6, at the desirable elevation for axially aligning said coupler with the corresponding coupler 7', at the adjoining end of the car 2. It is observable the beam 24 is conveniently of corresponding stock to that of the posts 6, and that the web 27 thereof is in abutment against the post front flanges 5; while the beam 24 is reinforced by a diagonal brace 28 united to the medial part of the web 27 and the inner vertical edges of the post rear flanges 5' by welds 29, 30, respectively. The shank 31 of the coupler 7 is afforded substantial bearing on the upper edge of a somewhat triangular strap-like support 32, including an outer rounding as at 32', said support having the inner ends in abutment with and welded to the outer face of the beam web 27 at 33, and also seating on the lower flange 34 of the beam 24 and similarly attached to said flange. The support 32, it is to be also remarked, is further sustained by oblique braces 36 secured thereto by welds 37, with corresponding welds 38 uniting them to the upper flange of the carrier beam 24, as readily understood on an inspection of Fig. 1, more particularly. The coupler shank 31 passes through a corresponding-section aperture 39 in the web 27 of the carrier beam 24, and is fitted with rectangular plate washers 40 as well as a retainer key 41; while it is observable the lower portion 7" of the coupler 7 is afforded a restricted degree of arcual movement, incident to coaction of said portion 7" with the support rounding 32'.

The means for carrying the "jack" 8, with freedom for vertical adjustment, consists of a movable channel-section beam 42, afforded guidance by flat bars 43 in spaced parallel relation to the forward flanges 5, of the posts 6, said bars having their lower portions inwardly-angled at 44, to seat on the upper flange of the coupler beam 24, and rigidly attached thereto by welds 45. On the other hand the upper ends of the bars 43 are stepped approximately Z-fashion, at 46 and secured in abutment to the flanges 5 by a weld 47. 75

Inclined struts 48 are welded to the lower angular bends of the bars 43, at 49, and to the forward ends of the device base angles 11, at 50, to rigidly brace the parts connected thereby; while a cross-tie 51 connects the forward angles 11 in parallel.

The "jack" beam 42, as best understood from Figs. 2 and 4, is of an over-all length in excess of the width across the posts 6; while the upper and lower flanges 52, 52' thereof are provided with notches 53 for sliding coaction with the post forward flanges 5, whereas the web portion of said beam similarly coacts with the bars 43 for vertical guidance, in an obvious manner. The beam 42 is preferably reinforced by a rearwardly-directed truss-structure comprising an angled-brace 54 with a center post 55 and spacedly-related reverse-inclined ties 56; all of said parts 54—56 being rigidly-united to the web of the beam 42, intermediate the flanges 52 thereof, by welds 57. It will now be readily understood the beam 42 is fabricated to resist the compression-thrust exerted by the "jack" 8, when in action, as later on explained.

The "jack" 8 may be of any appropriate form, 25 for instance, one comprising a gear-and-pinion drive-attachment 58 operated by a reversible pressure-air motor 59, both securely attached to the beam 42, and said motor including a piston 60 having a head 61, all in accordance with known practice.

For raising or lowering the "jack" 8, with the 30 associated carrying-beam 42, an over-reaching or yoke hanger 62 is securely fixed at 63 to the upper inner parts of the straightening-device posts 6, said hanger having suitable provision, at 64, for suspension of a conventional chain-hoist 65, or the like, with a suitable cable 66. A lifter or bail 67, is appropriately attached by fastening means 68 to the vertical flange of an angle-member 69, permanently secured to the underside of the supporting beam 42 and "jack" 8, in forwardly-spaced relation to the web of said beam 42; while said bail 67 is provided with a suitable link 70 for engagement by the hook 71, at the free end of the cable 66.

In order to provide adequate support for appropriate straightener elements 72, see Fig. 1, the angle-member 69 is fitted with spaced underlying stepped-straps 73, conveniently attached thereto by welds 74, said straps affording slideable guidance for flat bars 75 having the rear ends conveniently shaped at 76 to afford means whereby they are more easily moved forward—or retracted—into or from abutment with the car end 3. The straightener elements 72 are preferably in the form of blocks grooved, as indicated at 77, for engagement over the corrugate stiffeners 78, or the upper angle reinforce 79, commonly forming a part of railroad car ends, as readily understandable from Fig. 1.

To hold the device 4 rigid, when moved into operative position, relative to the distorted end 3 of the car 2, with the couplers 7, 7' mutually engaged, means such as opposing clamp elements 80 are preferably provided at the lower ends of the respective posts 6, as well as in connection with the outer rear portions of the T-bar base members 10 and united ends of the diagonal braces 21. These clamp elements 80 are preferably in the form of step or joggled members having the lower ends angled inwards at 81 for snug engagement below the head or ball portion of the rails 1, while said members are retained in assembly by through bolts 82 with wedge-keys 83, all as readily understandable by those con-

versant with the art. Obviously other suitable fastening means, instead of the clamp elements and key-bolts 82, may be employed for securing the device 4 to the rails 1.

To afford a convenient station for the operator, of the device 4, a platform 84 is provided rearwardly of the posts 6. This platform is, preferably, attached by carriage bolts 85 to angle-bars 86, 87 respectively secured across the rear flanges 5' of the posts 6 and to the struts 18, 10 all as readily understandable by those acquainted with the art. Thus it will be apparent that an operator standing on the platform 84 is in a most convenient position to manipulate the hoist 65 as well as control actuation of the "jack" 8. A tool-box 88 may, also, be mounted intermediate the leg portions of the T-section base members 10 in abutment with the post flanges 5'.

Having fully outlined the structural aspects of the improved car end straightening-device 4, the 20 use and operation thereof is briefly as follows:

Assuming, as hereinbefore indicated, that a "standing" or braked gondola car 2 has the end "bulged" out, as shown at 3 in Fig. 1, the device 4 is suitably transported or moved to the rails 1, whereon the car 2 is located, and suitably positioned with the base members 10, 11 seated on the ball portions of said rails with the clamp elements 88 loosely engaging said rail at both sides thereof; whereupon the device 4 is pushed, or otherwise forced, towards the car end 3 until the couplers 7, 7' interengage, when the clamp bolt keys 83 are driven tight to hold the device 4 rigidly in position. The operator next raises or lowers the "jack" 8 to the desired elevation, and then pushes the bars 75 towards the distorted car end 3, until their forward extremities abut said car end, whereupon the necessary block 72, or a plurality of such blocks 72 as shown with an associated bridging piece 72', is seated 40 across the bars 75.

Air under pressure is now admitted to the reversible motor 59, from any controllable source—not shown—to effect advancement of the actuator 60, for force abutment of its head 61 against the block 72, whereupon it will be readily apparent that under continued pressure exerted by the air, the bulged-out end 3 will be pushed or shoved back into its normal position without removal of the car end. When the car end has assumed the normal straightened out position, the motor 59 is reversed, and the head 61 will obviously be retracted, whereupon the block or blocks 72 is, or are, removed and the car again is in proper service condition. It will, also, be readily understood that car loads of long material can be pushed back on the truck, concurrently with, or without, effecting the straightening operation; while the steel ends of box cars, both plain and corrugated, can be straightened by simply elevating the "jack" 8, by means of the hoist 65, to the desirable level for effecting the restorative operation above explained. Particular attention is directed to the fact that, in actual practice, car ends, such as 3, have been straightened-out by the device 4 herein disclosed in less than one-half hour, as contrasted with an expenditure of from 7 to 9 man hours, under prevailing practice; while it is further worthy of notation that, by connecting the device 4 to the coupler 7' of the car 2 to be operated on, and by clamping the base member 10, 11 firmly to the heads of the rail 1, that the thrust of the plunger head 61 is effectively and rigidly opposed by the car 2 jointly with the clamp means 80, 75

and thereby greatly facilitating the straightening operation.

In conclusion, while it is self-evident that the illustrated embodiment of the invention, herein disclosed, adequately fulfills the objects and advantages primarily set forth, it is to be understood the said invention is subject to variation, modification, and other application, within the spirit and scope of the following claims.

Having thus described my invention, I claim:

1. A portable device for restoring the distorted walls of railroad cars and the like to normal condition comprising side components of inverted T-formation with vertical united channel-sections defining spaced posts having rearwardly and forwardly extending base supports directly alignable with and placeable on top of railroad rails; side struts and lateral braces connecting the side components in rigid parallelism; a stationary reinforced beam permanently secured across the columns and affording bearing for a forwardly-directed car-coupling adapted to interengage the conventional coupler means of an adjoining car end; a transverse reinforced beam vertically guided by the spaced posts, said beam being located above the car coupling and affording rigid support for a horizontally-effective thrust-mechanism; a hanger-bracket carried by and projecting forwardly over from the upper part of the spaced posts; a hoist suspended from the hanger-bracket adapted for elevating the thrust-mechanism to the desired level for effecting the car wall straightening-operation; slideable bars carried by the movable beam for projection into contact with the adjoining car wall to be straightened, said bars jointly affording support for a straightener-element; a platform projecting rearwardly from the spaced posts for the operator of the device; and longitudinally-spaced means associated with the column lower ends and the base support rear ends for rigidly clamping the portable device alignedly on the heads of railroad rails, whereby the active stroke of the thrust-mechanism is effectively and rigidly opposed by the car being operated on and the means clamping said device to the railroad rails.

2. A portable straightening-device, as defined in claim 1, wherein the side components consist of opposingly-related channel-section posts having integrally connected rearward base supporting portions of inverted T-section and aligned substantially-shorter base supporting portions of angle-section; a T-section rigidly connects the posts at their upper ends; the side struts consist of angle-sections respectively connecting the outer ends of the rear base supporting portions to the upper ends of the posts, and the outer ends of the forward base supporting portions to an intermediate point in the height of said posts; intersecting diagonal-braces connect the rear side struts; and a tie rod intervenes the outer ends of the forward base supporting portions of angle-section.

3. A portable straightening-device, as defined in claim 1, wherein the stationary beam consists of a channel-section rearwardly reinforced by a diagonal-brace, said brace integrally connecting the medial web-portion of the beam to the relatively remote vertical edges of the leg sections of the inverted T-section side components; and an angular strap having a medial rounding with obliquely related braces is integrally secured edgewise-vertical intermediate the channel-sec-

tion flanges to afford rigid bearing for the car-coupler.

4. A portable straightening-device, as defined in claim 1, wherein the movable beam consists of a channel-section having the flanges spacedly notched for sliding coaction with the leg-section parallel edges of the inverted T-form side components; a truss reinforcing-structure including an angled brace-bar, with a center post and reversely inclined ties, intervenes and is permanently secured to the web and flanges of the channel-section; and means whereby a suitable power-actuated thrust-mechanism is attachable to said movable beam.

5. A portable straightening-device, as defined in claim 1, wherein the hoist sustaining hanger-bracket consists of a semi-arched yoke having a medial suspension-eye, the ends of said yoke being integrally-secured to the upper inner parts of the side component spaced posts; and the hoist is of the chain type.

6. A portable straightening-device, as defined in claim 1, wherein the clamp means consist of

oppositely-related transversely-joggled elements having the lower ends inwardly turned; and key-bolts to adjustably secure said elements to the lower parts of the inverted T-formation side components in longitudinally spaced relation.

7. A portable straightening-device, as defined in claim 1, wherein the slidable members for support of the straightener-element are in the form of flat bars having the inner ends shaped for easy handling; and said members are movably supported by stepped straps, integrally attached to the underside of the movable beam, in transversely spaced position between the device side components.

8. A portable straightening-device, as defined in claim 1, wherein the guides for the movable beam are defined by the forward faces of the respective side component post sections, and flat bars spacedly attached to said sections are suitably angled at their respective ends to complete the guideways.

HARRY J. FREEMAN.
